PORATION OF PENNSYLVANIA

SPINDLE RECIPROCATING MECHANISM

Application filed August 13, 1929. Serial No. 385,603.

Our invention relates to mechanism for imparting a reciprocating movement to a rotating spindle and is designed primarily for reciprocating the wheel spindle of a grinding machine.

An object of the invention is to provide new and improved means for varying the distance through which the spindle reciprocates and for cushioning the connection between the driving means and the spindle reciprocating mechanism.

A further object is to provide means for quickly stopping the spindle reciprocating mechanism when it is disconnected from the driving means.

Further objects and advantages will become apparent as the description proceeds.

Referring to the accompanying drawings which are made a part hereof and on which similar reference characters indicate similar parts,

Figure 1 is a sectional front elevation of a portion of the wheel base of a grinding machine,

Figure 2 is a section on line 2—2 of Fig. 1,

Figure 3 is a sectional side elevation through the wheel base showing details of our device, and

Figure 4 is an isometric view showing an adjustable eccentric disk for reciprocating the spindle.

In the drawings reference character 10 indicates a wheel base for a grinding machine in which is rotatably mounted a spindle 11 on which a grinding wheel, not shown, may be mounted. Numeral 12 indicates a bracket in which is mounted a set of bearings in which the shaft 11 is rotatably carried. Bracket 12 is mounted on a base portion 13 in which it slides. A guide abutment 14 to which is secured a bracket 15 holds the bracket 12 in place. The spindle 11 has a driving gear 16 mounted thereon, which gear meshes with and drives a gear 17 on a shaft

18 which shaft is parallel with the shaft 11. The gear 17 is resiliently secured to the shaft 18 by means of a spring 19 which is passed through the shaft and secured to the hub of the gear 17 at 20 and 21. Driving connection 50 between the shaft 11 and the shaft 18 is

therefore cushioned by means of the spring 19. This prevents a sudden jar to the reciprocating mechanism which would otherwise be given it due to the inertia of the wheel spindle and the heavy grinding wheel 55 which is mounted on it.

Shaft 18 has a worm gear 22 which meshes with a worm wheel 23 which latter wheel is mounted to rotate freely on a shaft 24. The worm wheel 23 has a clutch element 25 on one face which is engageable by a corresponding clutch 26 on one end of a spool 27, the other end of this spool has clutch teeth 28 which are engageable with teeth 29 on a plate 30 which is secured to the wheel base 10. The 65 spool 27 is keyed to the shaft 24 so as to rotate the shaft but is permitted axial movement along the shaft to bring the teeth 26 or 27 into engagement with the teeth 25 or teeth 29 as desired. The spool 27 is axially moved 70 along the shaft by means of a bar 31 having a knob 32 on its forward end. This bar has a bracket or finger 33 secured to it which finger extends between the disks on the spool by which the spool is engaged to be moved axial- 75 ly of the shaft 24. The bar 31 has notches 34 and 35 engageable by a spring-pressed ball latch 36, the latch serving to hold the spool in position to hold the teeth engaged with the stationary plate 30 or with the rotating gear 23. The front end of the shaft 20 is mortised to fit a slot 39 in an eccentric block 37, the block 37 being held on the end of the shaft 24 by means of a screw 38. The slot is somewhat longer than the diameter of the shaft so 80 that the position of the eccentric block on the shaft may be varied to vary the eccentricity of the disk 37 with respect to the shaft 24. The disk 37 fits in a socket in a yoke 40 which is pivotally secured at 41 to the bracket 12. A cap 42 is secured to the yoke by means of screws 43 for holding the disk 37 in the yoke.

The operation of the device is as follows: The spindle 11 is driven by any suitable mechanism for driving the grinding wheel. When the operator wishes to reciprocate the wheel 11 he pulls the knob 32 outwardly until it is locked in this position by ball latch 36 dropping into the depression 35. This holds the 100

- teeth 26 in engagement with the teeth 25 on the worm wheel 23. This worm wheel is driven from the shaft 11 through the gears 16 and 17, the gear 17 being resiliently keyed to the shaft 18. The driving connection just described rotates the shaft 24 on the end of which is an eccentric disk 37, which disk upon rotating moves the yoke 40 to reciprocate the spindle 11 by means of bracket 12.
- 10 In order to change the distance through which the spindle reciprocates the screw 38 is loosened and disk 37 adjusted to give the amount of reciprocation desired. If the operator wishes to stop reciprocation of the 15 spindle he simply pushes the bar 31 inwardly until the latch 36 engages in the socket 34, at which time the teeth 38 will engage teeth 29 and instantly lock the shaft 24 against rotation.
- 20 From the foregoing description it will be seen that we have provided a device for reciprocating a wheel spindle which is very simple in construction and which provides suitable resilient drive between the driving 25 mechanism and the heavy reciprocated mechanism.
- It will be obvious to those skilled in the art that various changes may be made in our device without departing from the spirit of 30 the invention and we, therefore, do not limit ourselves to what is shown in the drawings and described in the specification but only as indicated in the appended claims.
- Having thus fully described our said invention, what we claim as new and desire to 35 secure by Letters Patent, is:
1. In a grinding machine having a wheel base and a grinding wheel spindle rotatably mounted in the wheel base, a bracket secured 40 to the spindle but allowing the spindle to rotate therein, a shaft parallel with the wheel spindle, resilient driving connection between the spindle and the said shaft, a second shaft and an eccentric on said second shaft, a yoke secured to the said bracket and having the eccentric operable in a socket therein, means for operatively connecting the second and the last-named shafts whereby rotation of the wheel spindle rotates the last-named shaft to 45 effect reciprocation of the wheel spindle, and means for locking the last-named shaft against rotation upon its being disconnected from the driven shaft, substantially as set forth.
  - 50 2. In a grinding machine having a grinding wheel base, a bracket slidably mounted in said base, a grinding wheel spindle mounted in said base and in said bracket, a driven shaft parallel with the wheel spindle, a resilient driving connection between the wheel spindle and the driven shaft, a second shaft rotatably mounted in the wheel base, a worm wheel loosely mounted on said shaft, driving connection between the driven shaft and said worm wheel, means for locking said worm 55 wheel to the second shaft to impart rotary motion thereto, a yoke connected to the said bracket, an eccentric on the end of the second shaft engageable with the yoke whereby rotation of the second shaft will impart a reciprocating movement to the yoke to the bracket and to the wheel spindle, substantially as set forth.
- 70 3. In a grinding machine having a grinding wheel base, a bracket slidably mounted in said base, a grinding wheel spindle mounted in said base and in said bracket, a driven shaft parallel with the wheel spindle, a resilient driving connection between the wheel spindle and the driven shaft, a second shaft rotatably mounted in the wheel base, a worm wheel loosely mounted on said shaft, driving connection between the driven shaft and said worm wheel, means for locking said worm 75 wheel to the second shaft to impart rotary motion thereto, a yoke connected to the said bracket, an eccentric on the end of the second shaft engageable with the yoke whereby rotation of the second shaft will impart a reciprocating movement to the yoke to the bracket and to the wheel spindle, substantially as set forth.
- 80 3. In a grinding machine having a grinding wheel base, a bracket slidably mounted in said base, a grinding wheel spindle mounted in said base and in said bracket, a driven shaft parallel with the wheel spindle, a resilient driving connection between the wheel spindle and the driven shaft, a second shaft rotatably mounted in the wheel base, a worm wheel loosely mounted on said shaft, driving connection between the driven shaft and said worm wheel, means for locking said worm 85 wheel to the second shaft to impart rotary motion thereto, a yoke connected to the said bracket, an eccentric on the end of the second shaft engageable with the yoke whereby rotation of the second shaft will impart a reciprocating movement to the yoke to the bracket and to the wheel spindle, substantially as set forth.
- 90 In witness whereof, we have hereunto set 95 our hands at Waynesboro, Pennsylvania this 10th day of August, A. D. nineteen hundred and twenty-nine.
- HAROLD E. BALSIGER.
